CLAIM

The ornamental design for an air freshener device, as shown
and described.

DESCRIPTION

FIG. 1 is an isometric view of the front housing of an air
freshener device, wherein the air freshener device is com-
prised of a front housing, a dome, and a rear housing;
FIG. 2 is a front view of the air freshener device;
FIG. 3 is a left view of the air freshener device;
FIG. 4 is a right view of the air freshener device;
FIG. 5 is a back view of the air freshener device;
FIG. 6 is a top view of the air freshener device; and,
FIG. 7 is a bottom view of the air freshener device.
The broken lines shown in the drawings illustrate portions of
the air freshener device and form no part of the claimed
design.
